(57) CLAIM

The ornamental design for a flask, as shown and described.

DESCRIPTION

FIG. 1 is a front perspective view of the flask, illustrating my new design;

FIG. 2 is a front facing view thereof, the rear facing view being a mirror image;

FIG. 3 is a left side view thereof, the right side view being a mirror image;

FIG. 4 is top plan view thereof; and,

FIG. 5 is a bottom plan view thereof.

The broken lines shown are included for the purpose of illustrating the unclaimed portions of the article and form no part of the claim.
